DRAINER BASKET

Kurt E. Christoffersen, East Hampton, Conn., assignor to
The Artistic Wire Products Co. of Conn., Incorporated,
Norwich, Conn., a corporation of Connecticut

Filed July 8, 1960, Ser. No. 61,272

Term of patent 14 years

(Cl. D44—29)

Fig. 1 is a top plan view of a drainer basket embodying my new design.

Fig. 2 is a side elevational view thereof.

Fig. 3 is an end elevational view.

Fig. 4 is a top perspective view thereof.

I claim:

The ornamental design for a drainer basket, substantially as shown.
